UNITED STATES PATENT OFFICE.

LEE O. GARRAWAY, OF MEMPHIS, TENNESSEE.

FOLDING EXTENSION-LADDER.

1,085,563.

Specification of Letters Patent. Patented Jan. 27, 1914.

Application filed December 14, 1912. Serial No. 736,809.

To all whom it may concern:

Be it known that I, LEE O. GARRAWAY, citizen of the United States, residing at Memphis, in the county of Shelby and State 5 of Tennessee, have invented certain new and useful Improvements in Folding Extension-Ladders, of which the following is a specification.

This invention relates to combined extension and step ladders, and has for one of its 10 objects to improve the construction and increase the efficiency and utility of devices of this character.

Another object of the invention is to produce a device of this character comprising a 15 plurality of foldable step-ladders which when united and extended form an extension ladder.

With these and other objects in view, the 20 invention consists in certain novel features of construction as hereinafter shown and described and then specifically pointed out in the claims, and in the drawings illustrative of the preferred embodiment of the invention: Figure 1 is a perspective view of the improved device arranged as an extension ladder. Fig. 2 is a perspective view of one of the ladder sections folded or collapsed. Fig. 3 is a sectional detail on the 25 line 3—3 of Fig. 1. Fig. 4 is a section of one of the steps or treads on the line 4—4 of Fig. 3. Fig. 5 is a perspective view of the structure as shown in Fig. 1 with one ladder folded and the other open. Fig. 6 is a perspective view of the structure as 30 shown in Fig. 1 with both ladder sections folded.

Corresponding and like parts are referred to in the following description and indicated in all the views of the accompanying drawings by the same reference characters.

The improved device comprises in general a plurality of foldable ladder sections of relatively short lengths which are independently foldable into a small space when not in use and adapted to be united end to end when extended to form an extension ladder. Any required number of the sections may be employed, but for the purpose of illustration two of the sections are shown united end to end. The ladder sections are precisely alike and each comprises two sides spaced apart a distance equal to the lengths of the treads or steps of the ladder, and as 45 the sides are precisely alike the description of one will suffice for all. Each side com-

prises spaced side members 10—11, preferably of wood and of sufficient size to withstand the strains to which they will be subjected. At one end the sides 10—11 are connected by a chock or filler piece 12 and are likewise connected at their other ends by a strap or plate 13 bent at the ends into sockets or sleeves 14—15 engaging closely around the upper ends of the side members. 60 The members 10—11 are connected near their upper ends by a rod 16 which likewise extends through the sleeves 14—15 and thus firmly unites the sleeves and their connecting plate or strap to the side members. The 70 straps or plates 13 of the various ladder sections are formed with projecting tongues which are rolled into cylindrical form, as shown at 17, to receive a hinge pintle represented at 18, which pintle being enlarged 75 at one end into a finger grip to enable the pintle to be readily inserted and removed. The plates 13 and their connected sleeves thus possess the two-fold function of a means for uniting the sides 10—11 of the 80 ladder sections, and likewise as means for hingedly uniting the ladder sections end to end. By this simple means, it will be obvious that a plurality of the ladder sections may be united end to end to form an extension ladder, while, at the same time, separable to form a plurality of relatively short ladder sections. 85

Each of the ladder sections is provided with a plurality of steps which are formed to fold inwardly to enable the side members to be disposed side by side in close relation when the ladder sections are folded. The side members 10—11 may be of any required length and arranged to receive any required 90 number of the folding steps, but for the purpose of illustration each section is shown provided with three sets of the steps, and as the sets are precisely alike the description of one will suffice for all. A strap or plate 19 is extended across the side members 10—11 where each of the steps is to be located and rolled into sockets or sleeves 20—21 at the ends to bear around the side members in the same manner as the sleeves 14—15. A 105 tie rod 22 extends through each of the sleeves 20—21 and the portions of the side members inclosed thereby and thus firmly unite the side members. The rods 22 serve the two-fold purpose of intermediate supports for the side members and likewise as supports for the outer ends of the steps. 110

Each step is formed in two portions hingedly mounted at their outer ends upon the rods 22 and hingedly united at their inner contiguous ends, so that the steps fold 5 upwardly and permit the sides to be disposed in close relation side by side. Each step section comprises a sheet or plate metal shell 23 bent at its edges around a core 24 of wood or like material, the shell structure 10 extending for a relatively short distance over the upper face of the core, as shown at 25 in Fig. 4. By this means, the steps are reinforced and supported by the wooden core, while, at the same time, the core is 15 protected from abrasion at the overturned portions 25. At their outer ends the bottom portions of the shells 23 are turned downwardly as shown at 26 and bear by the down-turned portions against the inner faces of 20 the plates or straps 13 and 19 when the step sections are in longitudinal alinement, as shown in Fig. 3. The terminals of the core portions 24 of the step sections are chamfered or beveled to enable the steps to 25 be more readily folded. The rods 22 extend through the cores 24 and the vertical sides of the shells 23 as shown, whereby the steps are hingedly united to the side members 10-11. At their confronting ends the step 30 sections are hinged together, as shown at 27. It will be noted that the hinges 27 are located upon the lower faces of the step sections so that when the latter are arranged in longitudinal alinement or end to end, as 35 shown in Fig. 1, the upper portions of the cores 24 and the ends of the shell including the guard portions 25 bear against each other and thus effectually prevent the deflection of the step. The pintles 28 of the 40 hinges 27 are extended rearwardly and connected by a coupling bar 29 so that when one pair of the steps is elevated the remaining steps will be simultaneously elevated therewith and "buckled" into folding position 45 as hereafter explained.

Pivoted at 30-31, respectively, to the sides 10-11 near one end are brace bars 32-33. At the ends opposite to the pivots 30-31 the bars 32-33 are longitudinally 50 slotted, as shown at 34-35, and arranged to be engaged by their slots over clamp bolts 36-37, the latter being tapped into the sides 10-11. By this arrangement, when the ladder sections are disposed in closed position, 55 as shown in Fig. 2, the bars 32-33 slide over each other and move by means of their slots 34-35 over the clamp bolts 36-37, it being understood that the nuts of the latter are first loosened to permit this movement.

60 The ladder sections are thus readily foldable

into relatively close relations for transportation or storage. After the ladders have been thus collapsed, the nuts of the clamp bolts 36-37 are tightened to hold the ladder sections in their closed position.

65

By this arrangement, it will be obvious that a plurality of foldable step ladders are provided which may be used separately or united by means of the socket hinges into an extension ladder which may be folded or 70 extended as required. By this arrangement, the ladder sections may be folded without disconnecting, or folded after they are disconnected as may be preferred.

75

The portion 26 of the step is preferably 75 folded upon itself to produce two thicknesses of the material, to strengthen and reinforce the step structure where the greatest strains occur, as a strong outward strain is produced between the step and the straps 19 80 when weight comes upon the steps. This is an important feature of applicant's device and adds materially to its efficiency and utility without material increase in weight or expense.

85

Having thus described the invention, what is claimed as new is:—

1. In a foldable step ladder, a plurality of sections adapted to be arranged end to end and each including longitudinal members 90 spaced apart, a strap extending transversely of each of said longitudinal members at their confronting ends and bent to form spaced sockets adapted to receive the longitudinal members, the material forming the straps 95 being pressed outwardly between the sockets to form hinges, tie rods extending through the sockets and the portions of the longitudinal members inclosed thereby, and steps mounted to swing upon said rods.

100

2. In a step ladder, sides each including longitudinal members spaced apart, a plurality of connecting members each comprising a strap extending transversely over the longitudinal members and bent to form 105 spaced sockets adapted to receive the terminals of the longitudinal members, the material forming the straps being pressed outwardly between the sockets to form hinges, tie rods extending through the sockets and 110 the portions of the longitudinal members inclosed thereby, and steps mounted to swing upon said rods.

105

In testimony whereof I affix my signature in presence of two witnesses.

LEE O. GARRAWAY. [L. S.]
